UNITED STATES PATENT OFFICE.

HENRY E. BIGGINS, OF WALLINGFORD, CONNECTICUT.

TRAVELER'S SHAVING-MUG.

1,053,559.

Specification of Letters Patent. Patented Feb. 18, 1913.

Application filed December 15, 1911. Serial No. 665,981.

To all whom it may concern:

Be it known that I, HENRY E. BIGGINS, a citizen of the United States, residing at Wallingford, in the county of New Haven 5 and State of Connecticut, have invented a new and useful Improvement in Travelers' Shaving-Mugs; and I do hereby declare the following, when taken in connection with the accompanying drawings and the letters 10 of reference marked thereon, to be a full, clear, and exact description of the same, and which said drawings constitute part of this specification, and represent, in—

Figure 1 a view partly in side elevation 15 and partly in vertical section of one form which my improved traveler's shaving mug may assume, the cover being shown in its open position by broken lines. Fig. 2 a view thereof in front elevation with the 20 cover raised. Fig. 3 a plan view of the mug with the cover removed. Fig. 4 a detached perspective view of the tapering container.

My invention relates to an improvement 25 in travelers' shaving mugs, the object being to adapt a shaving mug to receive and contain a razor, soap-box and brush, so that an individual shaving mug may be combined with the advantages of the shaving 30 case ordinarily carried by the traveler for the reception of his shaving appliances.

With these ends in view, my invention 35 consists in a shaving mug having certain details of construction and combination of parts as will be hereinafter described and pointed out in claim.

In carrying out my invention as herein shown, I employ a metal shaving mug 2 having a hinged cover 3, a handle 4, a base 40 5 and a lip 6, the cover being provided upon its inner face with a circular shaving mirror 7. Within this cup I locate a removable

sheet-metal container consisting of a deep 45 tapering sleeve 8 the taper of which conforms to the taper of the inside of the mug, this sleeve being open at its top and bottom and provided upon its inner face with a sheet-metal socket 9 for the reception of a safety razor 10, with a wire clip 11 for the 50 reception of a shaving-brush 12, and with a collar 13 for the reception of a small cy-

lindrical soap-box 14 containing shaving soap. It will be understood that the razor 10, brush 12, and shaving-soap box 14 may be of any standard form, size and construction. Just within the upper edge of the container 8, I locate three finger-buttons 15 arranged at equal distance from each other between the socket 9, clip 11 and collar 13, these finger-buttons 15 being provided to 55 permit the container to be readily lifted out of the mug as well as gently let down into the same.

In using my improved device, any one 60 of the finger-buttons 15 is engaged by the forefinger and the container 8 lifted bodily out of the mug and set down upon its lower end as upon a base. The razor, shaving brush and soap box may now be removed 65 from the container, and preparation for shaving made, the mug, which is now entirely free, being used for the lather, and the mirror being used for the shaving operation. After shaving, the mug is rinsed out 70 and the razor, brush and soap-box restored to the container, after which the same is let down into the mug and the cover closed. The mug now forms a compact, convenient 75 and safe package or case for the shaving appliances.

As shown the mug 2 is made of sheet metal, but the container 8 permits a glass or porcelain mug to be used if desired.

By making the tapered sleeve 8 conform 80 in its taper to the taper of the interior of the mug 2, the sleeve is firmly held against rattling, while by making the said sleeve open at the bottom, the brush 12 and box 14 will drain directly into the bottom of the mug. Moreover, by making the sleeve open 85 at the bottom, no suction is created to interfere with its removal from the mug.

I claim:—

In a traveler's shaving mug, the combination with a tapered mug, of a hinged 90 cover therefor, and a tapering removable sheet-metal sleeve corresponding in taper to the taper of the said mug, open at its top and bottom, provided upon its upper edge with one or more inwardly projecting finger-buttons by means of which it may be 95 lifted out of the mug and restored thereto,

and furnished with a razor-holder, with a brush-holder and with a soap-box holder, all extending inward from its inner face, whereby a razor, a shaving-brush and a 5 soap-box may be carried in the shaving-mug and removed therefrom together preparatory to shaving.

In testimony whereof, I have signed this specification in the presence of two subscribing witnesses.

HENRY E. BIGGINS.
